ATTORNEY

UNITED STATES PATENT OFFICE.

MEYER HALPERN, OF NEW YORK, N. Y., ASSIGNOR TO UNITED WIRE GOODS MANUFACTURING COMPANY, OF NEW YORK, N. Y.

DESIGN FOR A TUMBLER HOLDER.

● 60,534.

Specification for Design.

Patented Mar. 7, 1922.

Application filed August 27, 1921. Serial No. 496,177. Term of patent 7 years.

To all whom it may concern:

Be it known that I, MEYER HALPERN, a citizen of the United States, and a resident of the city, county, and State of New York, have invented a certain new, original, and ornamental Design for Tumbler Holders, of which the following is a specification, reference being had to the accompanying drawing, forming part thereof.

In the drawing:

I claim:

The ornamental design for a tumbler holder, as shown.

MEYER HALPERN.
